UNITED STATES PATENT OFFICE.

MAURICE E. JOYCE, OF WASHINGTON, DISTRICT OF COLUMBIA, ASSIGNEE OF ONE-HALF
TO GAIUS M. BRUMBAUGH, OF WASHINGTON, DISTRICT OF COLUMBIA.

FAUCET AND VALVE.

988,575.

Specification of Letters Patent.

Patented Apr. 4, 1911.

Application filed February 25, 1909. Serial No. 479,934.

To all whom it may concern:

Be it known that I, MAURICE E. JOYCE, a citizen of the United States, residing at Washington, in the District of Columbia, have invented certain new and useful Improvements in Faucets and Valves; and I do hereby declare the following to be a full, clear, and exact description of the invention, such as will enable others skilled in the art 10 to which it appertains to make and use the same.

My invention, stated in general terms, is a faucet or other valve provided with an improved automatic cut-off which under fluid pressure will close the passage through the valve-seat when the valve proper is removed from the case for inspection, adjustment or repair. In a water-spigot or faucet, for example, the automatic cut-off will thus prevent the water from spouting out and deluging the premises and person manipulating the faucet, when the screw-cap with the valve proper is unscrewed and detached to permit renewing the washer of the valve, or 25 grinding the valve-seat, or for other purposes.

The object of my invention is to provide a simple, practicable and efficient device of the above-stated character, and one that can 30 be manufactured at little more than the cost of manufacture of the ordinary faucet or valve.

I attain the object stated by means substantially as hereinafter described with reference to the accompanying drawings and more particularly pointed out in the claims annexed to this specification.

The invention is applicable to various sorts of cocks and valves, including steam 40 cocks, boiler and injector valves; etc., and hence I do not intend to restrict myself to the particular embodiments shown in the drawings wherein I have by way of example illustrated several constructional modifications of faucets embodying the invention.

Each figure of the drawing is a side elevation of a faucet having a portion of its body or case broken away and its revealed interior shown in section with parts in elevation.

Figures 1, 2 and 3 represent a preferred form of my invention in a faucet of standard or conventional type. Fig. 1 shows the valve seated or closed. Fig. 2 shows the valve raised from its seat to allow discharge 50 of water from the faucet. Fig. 3 shows the

faucet when its screw-cap together with the valve-stem and valve have been removed, the cut-off being in operation. Fig. 4 is a view like Fig. 1 showing a similar style of faucet with a modified form of embodiment of the invention.

Corresponding parts are indicated by the same reference symbols in the different figures.

In Figs. 1 to 3 inclusive, the faucet is of the screw-plug type commonly in use. 1 is its body, case or shell; 2 its screw-cap; 3 the valve-stem or spindle of the screw-plug; 4 the screw thereof, working in the female screw 5 in the case; and 6 an elastic packing, disk or washer, usually of fiber, leather or the like affixed to the foot of the screw-plug and constituting the valve-proper which seats over and closes the central orifice in the internal bridge or partition 7 dividing the inlet-chamber from the discharge-chamber of the faucet. A separate ring 8, secured in the said central orifice, furnishes the valve-seat 9 for the disk or washer 6.

Below the valve-seat, a swell or bulge of the faucet-case or shell 1 furnishes a chamber for a spherical valve or ball 10 which is adapted under force of the water pressure to rise and close the central orifice of the faucet from the bottom side; the aforesaid ring 8 also affording a valve-seat 11 to receive the ball. Under normal conditions, however, whether the faucet be opened or closed, the ball is prevented from seating by means of a stud or projection 12 depending from the valve-head and constituting a continuation of the valve-stem; which stud in practice may be an extension of the screw which secures the packing or washer 6 to the foot of the screw-plug. Hence, as will be observed, when the screw-plug is adjusted up to raise the washer 6 from its seat and thereby open the faucet, the rising of the ball 10 is restrained by the stud 12, thus maintaining the central orifice or passage 80 open to allow a full discharge of water from the faucet, as shown in Fig. 2. But when it is desired to inspect, adjust or repair the faucet, or to renew the washer 6, the screw-cap 2 is unfastened, thus allowing the screw-plug to be screwed out of the case, so that, the stud 12, being withdrawn, the ball 10 is free to rise and close the lower valve-seat 90 11, thus shutting off the water and preventing it from spouting out through the opened

100
105
110

top of the case. Upon replacing the screw-plug and its screw-cap 2, the stud 12 will again enter the ring 8 and push the ball 10 away from its seat, thus allowing the faucet 5 to be operated or controlled by the screw-plug alone in the ordinary manner.

The relative length of the stud 12 and range of motion of the ball 10 and adjustment of the screw-plug, are preferably such 10 that the ball will at all times be prevented from seating under ordinary operation of the faucet; that is, when the faucet is opened and the screw-plug is adjusted to its uppermost limit, determined by abutment of the 15 top of the screw 4 against the bottom side of the internal shoulder of the screw-cap 2, the stud 12 will protrude sufficiently to keep the ball unseated, as shown in Fig. 2. The same effect would be gained by locating the valve- 20 seat higher and proportionally reducing both the length of the stud and the depth of the chamber containing the ball, which would thus reduce the swell or bulge at the bottom of the faucet-case to approximately 25 the form of the ordinary faucet. But I do not confine myself to the relative proportions stated. The stud 12 may be relatively shorter, and the depth of the chamber containing the ball may be less, and the arrangement 30 may be such that when the screw-plug is adjusted all the way up the ball will seat within the lower side of the orifice and cut off the water. This latter arrangement would provide a two-fold valve, since the 35 water would be shut off by the disk or washer 6 when all the way down and by the ball 10 when the said disk or washer or valve proper is adjusted all the way up, so that, in case of a leaky or deteriorated 40 spigot, leakage would be avoided by the action of the ball when the faucet is turned off, in which event the faucet could be turned on to allow discharge of the water by adjusting the plug-valve to a position intermediate 45 its extreme limits.

The ball is kept in place or prevented from dislocation by a suitable cage or socket 13 formed or provided in the bottom of the passage case or shell, which confines the 50 motion of the ball and prevents it from passing from under the valve-seat. Within the cage, the ball has a free lateral play and may of course wobble more or less under the stud 12, as indicated by the full lines and 55 dotted lines in Fig. 2, but it will be prevented from passing out between the top of the case 13 and the bottom of the ring 8, so that when the stud 12 is withdrawn, the ball will be sure to seat and close the central orifice or passage. Instead of the cage 13, the 60 ball may be suitably confined by the shape and size of its chamber, that is by the configuration of the faucet-case, particularly where the stud 12 is shorter and the depth of 65 the ball chamber is less. If, for example,

the proportions should be such as to require only a slight vertical play of the ball, or if the ball should be relatively large in diameter, a small swell or bulge in the faucet-case would serve to confine the ball and prevent 70 it from passing laterally out of its proper chamber.

As the ball is intended to be raised by the water pressure back of the valve-seat, it is advisedly made light enough to float and 75 may be of aluminum, wood, cork or any other suitable material, or it may be a hollow metal ball; and it may even be of solid metal, fiber, glass, rubber or other suitable substance, if there is high pressure in the 80 pipe line sufficient to seat the ball when the restraining stud 12 is withdrawn. By using a hollow ball or other light ball, it would more readily seat even under very low water pressure. In any event, however, if the 85 water pressure should be too low to seat a relatively heavy ball, it would only be necessary to give the faucet a half turn in its coupling to the pipe line, thus inverting the faucet, whereupon the ball would of course 90 seat itself upon withdrawal of the stud.

The diameter of the ball is less than that of the central orifice in the bridge 7, but greater than the inside diameter of the seat-ring 8. Hence, in assembling the faucet, 95 the ball is first dropped through the said central orifice and the seat-ring 8 is then pressed or driven forcibly into place, the ring being preferably tapered and the walls of the orifice being similarly shaped to produce 100 a wedging effect and secure the seat-ring fixedly in place. It will thus be seen that the ball and seat-ring can be inserted through the bore of the screw-plug, before the latter is inserted; so that the construction shown avoids the necessity of an extra screw-cap or bonnet on the underside of the faucet-case and hence the faucet with the automatic cut-off can be manufactured at substantially the same cost as an ordinary 110 faucet, the only additional element being the ball. The insertion of the seat-ring as a separate piece is really an advantage, since the ring can be separately manufactured cheaper and better than by machining the valve-seat as a part of the case casting. Another advantage is that the seat-ring can be made of better wearing material than the cast brass or metal of the shell. I, therefore, consider the faucet shown in Figs. 115 1 to 3 as the best and most practicable of the several constructions illustrated.

The faucet shown in Fig. 4 is substantially similar to the construction already described, except in the following particulars: Instead of a separate seat-ring, the valve-seats 9 and 11, for the disk 6 and ball 10 respectively, are formed as integral parts of the bridge or partition 7; and in this connection, as the central orifice is of less di- 125 130.

ameter than the ball, the latter is inserted through the bottom of the faucet-case which for that purpose is provided with a detachable screw-cap or bonnet 14, said screw-cap or bonnet being socketed to receive and confine the play of the ball and thus taking the place of the cage 13 shown in the preceding figure. The operation is the same as already described.

10 My invention also contemplates the construction of the faucet or valve, as shown in Fig. 4, but without the detachable bonnet 14, by employing a yieldable, or resilient, or elastic ball, and forcing it through the central orifice, the latter being of less diameter than the ball. For example, a rubber-ball or a hollow-ball of resilient material may be forced through the orifice and afterward resume its spherical form. Another method 20 contemplated within this invention is to cast the ball in its chamber in the process of casting the shell or case.

While the principal feature of my invention is the ball-valve which seats itself under 25 the fluid pressure, thus dispensing with springs or other means for operating the cut-off, I also claim broadly and without limitation to the particular form of cut-off valve, the hereinbefore described constructions whereby the cut-off valve is inserted through the central orifice and thereby placed in position behind the main valve seat without the need of a screw-cap or bonnet on the underside of the case.

35 I reserve the right to such modifications as may be made in details of construction and arrangement within the scope of my invention, as defined in the following claims.

I claim as my invention and desire to secure by Letters Patent:

1. The combination of the valve-case or shell, a valve-seat therein, a main valve controlling the passage therethrough and adapted to seat upon the outlet side thereof, said main valve having a protrusion adapted to 40 project into said passage, a valve-stem carrying said main valve and protrusion, a spherical valve or ball on the opposite or inlet side of said valve-seat adapted to seat thereagainst under the fluid-pressure when 45 the valve-stem withdraws said main valve and protrusion, and a cage integral with and upstanding from the case for confining the motions of said ball and preventing lateral dislocation thereof.

2. A faucet having an integral shell provided with a single screw-cap which is above the valve-seat in said shell, a screw-plug the spindle of which fits in said screw-cap, said screw-plug working above said valve-seat and controlling the orifice therein, and a ball below said orifice and of larger diameter than said orifice, the bottom of the shell being formed to provide an upstanding ball chamber adapted to confine the play 55 of said ball and prevent its dislocation from under said orifice, the screw-plug having a protrusion which prevents the ball from seating until the screw-plug is raised sufficiently to withdraw said protrusion.

In testimony whereof I affix my signature, in presence of two witnesses.

MAURICE E. JOYCE.
